FLUID HEATER

Robert Jackson Horne, Jenkintown, Pa.

Application August 16, 1951, Serial No. 242,145

7 Claims. (Cl. 122—134)

1

This invention relates to fluid heaters and more particularly to a heater having a combustion chamber therein for providing hot water or other liquid for a variety of purposes, such as house heating, domestic hot water supply, process use, and other purposes, and for heating other fluids.

The fluid heaters heretofore available, comprising combinations of furnace and heat exchanger, have usually employed natural draft and an inefficient heat exchanger, or induced draft both with constant heat input or "on-off" control.

The fluid heaters heretofore available have had many serious limitations. With many of these heaters, high burning rates must be employed to maintain the stack temperature above the dew point of the water vapor formed as a product of combustion. The sulphur content of the fuel, when burned, produces sulphur dioxide, SO_2 which with the water of condensation produces active sulphurous acid, H_2SO_3 . This acid attacks the mortar of the stack or chimney, penetrates the interior walls and disintegrates the same and spoils the wall finish. This acid also forms under light load burning conditions in the last passes of the heater and is particularly corrosive to the sheet metal which is frequently used at these locations. Operation at desired fractional capacity is accordingly attended with objectional effects. When the temperature control no longer calls for heat, the fuel supply is shut off. The stack, in many instances, has been overheated to preclude condensation and in this condition continues to produce stack draft with forced ingress of air through the heater resulting in an attendant heat loss. Such air, upon its passage through the heater extracts heat from the liquid in the heater and discharges the extracted heat with the stack gases. At the same time, the stack is cooled down below the temperature corresponding to the dew point with resultant acid formation. The products of combustion, because of the hydrogen content of the fuel, contain large quantities of water vapor with a high heat content which passes off to the stack as a further loss.

The fixed heat losses of the heaters heretofore available may be summarized as: (1) overhigh stack temperature heat loss, (2) standby stack heat loss, and (3) loss of the higher heat value or vapor loss. These losses, as heretofore indicated, are accompanied by destructive action of sulphurous acid, and by ineffective heat control and ineffective heat transfer.

2

In accordance with the present invention, a heater is provided which overcomes the objections to the prior heaters.

In accordance with the present invention, also, a heater is provided with which the stack temperature is reduced to a minimum by employing counterflow heat exchange.

In accordance with the present invention, also, a heater is provided in which the standby stack loss is eliminated by use of pressure firing in place of natural draft.

In accordance with the present invention, also, a heater is provided in which the higher heat values of the fuel are recovered by recovery of the latent heat of vaporization in the flue gases.

In accordance with the present invention, also, the deterioration of the parts exposed to the combustion products is eliminated by the use of highly corrosion resistant materials.

In accordance with the present invention, also, a heater is provided which does not require a stack because of the use of forced draft, the use of counterflow heat exchange, and the low heat content in the products of combustion which are relatively free from condensable constituents, such as water.

In accordance with the present invention, also, a heater is provided in which the hazards of explosions and leakage of gas is eliminated.

In accordance with the present invention, also, a heater is provided having a controllable widely variable heat output.

Other objects and advantageous features of the invention will be apparent from the specification and claims.

The nature and characteristic features of the present invention will be more readily understood from the following description, taken in connection with the accompanying drawings forming part hereof, in which:

Figure 1 is a vertical central sectional view through a preferred embodiment of a heater in accordance with the invention, taken approximately on the line 1—1 of Fig. 2; and

Fig. 2 is a horizontal sectional view taken approximately on the line 2—2 of Fig. 1, parts being shown in plan to illustrate the details of construction.

It should, of course, be understood that the description and drawing herein are illustrative merely, and that various modifications and changes may be made in the structure disclosed without departing from the spirit of the invention.

Referring now more particularly to the draw-

ings, a cylindrical housing 10 is provided, of metal, having a vertical side wall 11 and a bottom wall 12 connected thereto in any desired manner such as by welding. The bottom wall 12 is preferably provided with a downwardly disposed or dished portion 13 for purposes to be explained.

The side wall 11 is provided, near the bottom thereof, with a flanged fluid inlet pipe 14 for the delivery into the heater of the fluid to be heated. The upper extremity of the side wall 11 is provided with a horizontal peripheral flange 15 which is adapted to have secured thereto, in fluid tight relation, a top closure wall 16. A gasket 17 is preferably interposed between the top wall 16 and the flange 15 and bolts 18 may be provided for removably holding the top wall 16 in position. At the central portion of the top wall 16, a removable cap 19 is provided having a flange 20. Studs 21 secured to the top wall 16 and extending through the flange 20 preferably have nuts 21 thereon, for removably holding the cap 19 in position. A gasket 22 is preferably interposed between the flange 20 and the top wall 16.

The cap 19 is preferably provided with an opening 25 which is closed by a resilient gasket 26, of fluid tight material such as rubber, natural or synthetic, through which a burner 27 extends, the opening 25 permitting the withdrawal of the burner 27 if desired or required.

The burner 27 preferably includes an exterior flanged flaring tube 28 for the delivery of air under pressure, and in the interior of the tube 28, a flaring fluid delivery tube 29 is provided, to which fuel under pressure is delivered by a pipe 30.

The burner 27 is adapted to be secured to the inlet of a combustion chamber 35, preferably having a threaded connection 36 permitting assembly and removal.

The combustion chamber 35 is preferably of U-shape and tubular and includes a vertical cylindrical section 37 made of temperature change and heat resistant glass, with a flaring rim 38 with which a clamping ring 39 is in engagement. The ring 39 has a plurality of clamping arms 40 which extend through the cap 19 and have nuts 41 on the outer end thereof for clamping, and a spacer sleeve 32 is provided for maintaining the spaced relation of the burner 27.

At the lower part of the vertical cylindrical section 37 of the combustion chamber 35, a U-shaped section 42 is provided, at the lower part of which a drain pipe 43 is connected. The section 35 preferably has a ring 44, of resilient material such as rubber, interposed between its exterior, and the interior face of the dished portion 13 for accommodating expansion and preventing breakage upon occurrence of shock. The space surrounding the lower end of the section 42, in the dished portion 13, and outside the ring 44 may, if desired, be filled with sand, as at 31, for further cushioning and support.

In order to prevent leakage at the drain pipes 43, a sealing plate 42a may be provided, for the reception of a sealing gasket 33. A sealing plate 42b, in engagement with the gasket 33 is preferably also provided and held in compressing relation to the gasket 33 by nuts 34 on studs 34a.

Within the interior space in the housing 10, a plurality of spiral units 45 are provided, each having an inner or central manifold section 46. The manifold sections 46 are disposed in vertical alinement, have ground or other fluid tight joints 47a therebetween, and constitute a portion of the

combustion chamber. At the upper end of the uppermost manifold section 46, a closure 48 is provided. A cushioning block 49, of resilient material such as rubber, is interposed between the closure 48 and the cap 19.

Each of the manifold sections 46 is made of temperature change and heat resistant glass and has extending therefrom a glass tube 45a, disposed in a spiral path in a plane, and the respective tubes 45a being arranged one above another. The tubes 45a are preferably terminated contiguous to the inlet pipe 14. The tubes 45a, are pitched downwardly to a slight extent towards their outer ends for drainage and at their outer ends, are each connected to tubular manifold sections 146, of glass, and similar to the manifold sections 46, in vertical alinement.

In the space below the lowermost tube 45a, a cushioning ring 50, of resilient material such as rubber, is provided for supporting the tubes 45a and resisting shocks.

At the upper end of the uppermost manifold section 146, a gas discharge connection 51 is provided which may be connected to any desired location for the discharge of the gases of combustion.

The connection 51 has a shoulder 52 for engagement with a resilient cushioning ring 53. Mounted on the top wall 16, a closure ring 54 is provided, having a lower flange 55, an upper flange 56 and an inwardly extending flange 57. The lower flange 55 is adapted to be removably connected to the top wall 16 by studs 58 and nuts 59, a gasket 60 being interposed between the flange 55 and the top wall 16.

The flange 57 is adapted to have the cushioning ring 54 in engagement therewith, and on the opposite side an inner sealing gasket 60, and an outer sealing ring gasket 61 held in position by a sealing plate 62 are provided for preventing fluid leakage.

Bolts 63, extending through the flange 56 and the plate 62 hold the plate 62 in position and compress the gaskets 60 and 62.

At the lower end of the lowermost manifold section 48, a liquid discharge pipe or connection 65 is provided for the discharge of condensate from the products of combustion, as hereinafter explained. The discharge connection 65 has a shoulder 66 for engagement with a resilient cushioning ring 67. Secured to the bottom wall 12, a clamping plate 68 is provided with which a sealing gasket 69 is adapted to engage, a sealing plate 70 being provided for compressing the gasket 69. Studs 71 and nuts 72 provide for tightening the plate 70 and compressing the gasket 69.

The pipe 65 is connected to a drain pipe 73 having an upwardly extending leg 74 connected to an upwardly extending leg 75 which in turn is connected to the drain pipe 43.

At the top of the legs 74 and 75 a fluid discharge pipe 76 is connected for determining the water level at the lower part of the combustion chamber 35 and for delivery of condensate, as hereinafter explained.

The top closure wall 16 is provided with a fluid outlet connection 77 for the heated liquid.

The mode of operation will now be pointed out. Fuel under pressure is supplied through the fuel pipe 30 to the burner 27, and air under pressure is supplied to the burner 27 for delivery through the pipe 28. The fuel and air thus delivered to the combustion chamber 35 is burned 75 in that chamber and while burning passes down-

wardly in the vertical section 32, around through the section 42 and upwardly through the manifold section 46. A portion of the liquid in the section 42 is vaporized by the radiant heat of combustion in the section 37 and the flame and hot gases in contact therewith. In the manifold sections 46, the hot gases of combustion are divided into a plurality of streams and pass outwardly through the spiral tubes 45a and to the manifold sections 146 for discharge through the discharge pipe 51.

The fluid to be heated is delivered through the inlet pipe 14, passes in heat-exchange relation with the exteriors of the manifold sections 146, with the spiral tubes 45a in an inward spiral path along these tubes, with the manifold sections 46, and with the combustion chamber section 37, and pass out through the outlet pipe 71.

Upon the completion of combustion, the water vapor produced as a result of the combustion of the hydrogen content of the fuel and the water vaporized in the section 42 passes with the other gases of combustion through the spiral tubes 45a. The gaseous streams in their passage through the spiral tubes 45a are drastically reduced in temperature and condense. The condensate passes outwardly in the spiral tubes 45a to the manifold section 146 where it is delivered to the discharge pipe 65. A high heat recovery from the fuel is thus achieved by utilization of the latent heat in the condensate which is available because of the low temperatures of the gases before discharge.

The lower part of the combustion chamber 35, because of the connection of the pipe 65 thereto preferably contains water which is available for vaporization in the combustion chamber 35, and for subsequent condensation in the outward passage of the hot gases through the tubes 45a. The pipe 76 prevents the water level in the combustion chamber 35 from rising too high and maintains the level at the desired location.

The construction of the combustion chamber 35, the spiral tubes 45a, and the manifold sections 146, of glass of the proper characteristics, prevents corrosion by sulphurous acid formed as a result of the combustion of the sulphur content of the fuel.

I claim:

1. A fluid heater comprising a closed casing having a fluid inlet and a fluid outlet, a combustion chamber centrally disposed in said casing, a burner at one end of said combustion chamber having fuel and air delivery connections for the delivery of air and fluent fuel under pressure, a first manifold in said casing in communication with said combustion chamber, a second manifold in said casing spaced from said first manifold and having a gas discharge pipe, and a plurality of tubes connecting said manifolds, each of said tubes being of spiral configuration and downwardly pitched toward the outlet end of said tube, and each of said tubes being in engagement with contiguous tubes above and below to provide a spiral path for the fluid to be heated.

2. A fluid heater comprising a closed casing having a fluid inlet and a fluid outlet, a combustion chamber centrally disposed in said casing, a burner at one end of said combustion chamber having fuel and air delivery connections for the delivery of air and fluent fuel under pressure, a first manifold in said casing in communication with said combustion chamber, a second manifold in said casing spaced from said first manifold and having a gas discharge pipe, a plurality of tubes connecting said manifolds, each of said

tubes being of spiral configuration and downwardly inclined toward the outlet end of said tube, and each of said tubes being in engagement with contiguous tubes above and below to provide a spiral path for the fluid to be heated, a liquid connection at the lower end of said combustion chamber, a liquid drain connection at the lower end of said second manifold, and connections between said liquid connections for determining the liquid level in the lower part of said combustion chamber.

3. A fluid heater comprising a closed casing having a fluid inlet and a fluid outlet, a combustion chamber centrally disposed in said casing, a burner at one end of said combustion chamber having fuel and air delivery connections for the delivery of air and fluent fuel under pressure, a manifold in said casing having a gas discharge pipe, a plurality of tubes of spiral configuration connecting said combustion chamber and said manifold, each of said tubes being downwardly pitched toward the outlet end of said tube, and each of said tubes being in engagement with contiguous tubes above and below to provide a spiral path for the fluid to be heated and a liquid drain connection at the lower end of said manifold.

4. A fluid heater comprising a closed casing having a fluid inlet and a fluid outlet, a combustion chamber centrally disposed in said casing, a burner at one end of said combustion chamber having fuel and air delivery connections for the delivery of air and fluent fuel under pressure, a manifold in said casing and having an upwardly extending gas discharge pipe, a plurality of superposed tubes each of spiral configuration in a horizontal plane connecting said combustion chamber and said manifold, each of said tubes being downwardly pitched toward the outlet end of said tube, and each of said tubes being in engagement with contiguous tubes above and below to provide a spiral path for the fluid to be heated, and a liquid connection at the lower end of said combustion chamber.

5. A fluid heater comprising a closed casing having a fluid inlet and a fluid outlet, a combustion chamber of U-shape centrally disposed in said casing, a burner at one end of said combustion chamber having fuel and air delivery connections for the delivery of air and fluent fuel under pressure, a first manifold forming part of said combustion chamber, a second manifold in said casing spaced from said first manifold and having a gas discharge pipe, a plurality of tubes connecting said manifolds, each of said tubes being of spiral configuration in a horizontal plane, downwardly pitched toward the outlet end of said tube, and each of said tubes being in engagement with contiguous tubes above and below to provide a spiral path for the fluid to be heated, a liquid connection at the lower end of said combustion chamber, a liquid drain connection at the lower end of said second manifold, and connections between said liquid connections for determining the liquid level in the lower part of said combustion chamber.

6. A fluid heater comprising a casing having a top and bottom wall and a vertical side wall therebetween, a fluid delivery inlet in the lower part of said side wall and a fluid discharge outlet in said top wall, a vertically extending combustion chamber of U-shape centrally disposed in said casing, a burner at one end of said combustion chamber having fuel and air delivery connections for the delivery of air and fluent fuel

under pressure, a first manifold in said casing forming part of said combustion chamber, a second manifold in said casing spaced from said first manifold and having an upwardly extending gas discharge pipe, and a plurality of superposed tubes each of spiral configuration in a horizontal plane connecting said manifolds, each of said tubes being downwardly pitched toward the outlet end of said tube, and each of said tubes being in engagement with contiguous tubes above and below to provide a spiral path for the fluid to be heated.

7. A fluid heater comprising a casing having a top and bottom wall and a vertical side wall therebetween, a fluid delivery inlet in the lower part of said side wall and a fluid discharge outlet in said top wall, a vertically extending combustion chamber of U-shape centrally disposed in said casing, a burner at one end of said combustion chamber having fuel and air delivery connections for the delivery of air and fluent fuel under pressure, a first manifold in said casing forming part of said combustion chamber, a second manifold in said casing spaced from said first manifold and having an upwardly extending 15

5
